BELT-CLEANER.

1,163,001.

Application filed June 8, 1915. Serial No. 32,959.

To all whom it may concern:

Be it known that I, RUSSELL S. GIBSON, a citizen of the United States, residing at Lockhart, in the county of Union and State of South Carolina, have invented a new and useful Belt-Cleaner, of which the following is a specification.

This invention has reference to belt cleaners and its object is to provide a simple form of tool whereby power belts are rendered clean on the pulley side or face, and hence are capable of better frictional engagement with the pulleys than before, so as to transmit a greater amount of power without slipping.

Heretofore it has been the custom to clean belts with belt cleaners provided with carding cloth or other material, which in practice is liable to seriously injure the belt in the cleaning operation.

After belts have been in use for some time the pulley engaging surface becomes charged with various materials causing the belt to slip, and then in order to restore the clinging or friction surface the materials with which the belt has become contaminated must be removed. Of course, card clothing does remove such materials, but it has the disadvantage of injuring the surface of the belt, and oftentimes tearing up the belt at the laps.

The difficulties heretofore encountered with hard and rough surfaces used in belt cleaners are overcome by the present invention which provides a back having handles at opposite ends for its ready manipulation, and this back has countersunk thereinto a block of elastic friction material; that is, material which is of a frictional nature with respect to leather or the like. Such a block is best made of rubber and is cemented to the back within the countersink or receptacle provided for it, and projects from the back sufficiently to present a broad bearing surface to the face of the belt engaging the pulleys. Experience has shown that such a belt cleaner is very effective, thoroughly cleaning the belt and removing all deleterious matter without injury of any kind and leaving the belt in much better condition than before treatment.

The invention will be best understood from a consideration of the following detailed description, taken in connection with the accompanying drawing forming part of this specification, with the further under-

standing that while the drawings show a practical form of the invention, the latter is not confined to any strict conformity with the showing of the drawings, but may be changed and modified, so long as such changes and modifications mark no material departure from the salient features of the invention.

In the drawings: Figure 1 is a perspective view of a belt cleaner constructed in accordance with the present invention. Fig. 2 is a longitudinal central section thereof. Fig. 3 is a cross-section of the belt cleaner.

Referring to the drawings, there is shown an elongated and usually, though not necessarily, rectangular backing 1 terminating at opposite ends in handle extensions 2. The backing 1 may conveniently be made of wood, but, of course, is susceptible of manufacture from other materials. The length of the backing 1 is sufficient to have the handles 2 freely clear the belt when the belt cleaner is applied to the belt with the length of the cleaner transverse to the length of the belt.

In one face of the backing 1, which may be more or less flat, there is produced a socket or receptacle 3 usually of rectangular outline, although such particular shape is not obligatory. Lodged in the socket or receptacle 3, which is in the nature of a seat, is a block 4 of rubber conforming quite closely to the seat 3 and held therein by a layer 5 of cementitious material, or in any other suitable way. The thickness of the block 4 is such that it projects for a considerable distance, say, a quarter of an inch, more or less, in a full sized cleaner, and presents an extended and substantially flat working face 6 in spaced relation to the backing 1. Ordinarily if the rubber block be about two by four inches in extent, and say half an inch or more thick, it is of ample size for many belts, but if it be desired to provide for larger belts, the block may be made longer, or even wider, although the block of the size named will answer for belts of considerably more than four inches in breadth.

The handles are made of sufficient size and suitably shaped for grasping in the hands of the user, so that in a practical form of the invention the backing may be nine or ten inches long and from two and one-half to three inches broad.

The cleaner may be used while the belt is

running and the plane rubber surface 6 is applied to the pulley side of the belt. The peculiar clinging qualities of the rubber surface cause it to so frictionally engage the belt that deleterious material thereon is loosened and removed from the belt, and the latter becomes markedly clean and presents a renewed friction surface toward the pulleys without any undue roughening, tearing or other injury to the wear surface, and without in any manner affecting the lap joints of the belt. The device works well on either the skin or the flesh side of the belt in accordance with which side is presented 15 toward the pulleys.

While rubber has been mentioned as a preferred material, it is to be understood that the invention is not of necessity limited to such precise material since any material having the qualities of rubber in being more or less tenaciously clinging, and at the same time more or less elastic or yielding, will answer the purpose.

It is to be understood that the term rubber as used throughout the description and in the claims is intended to include such other materials as may have the qualities or characteristics of the cleaning block of the present invention. Good results are obtained with vulcanized rubber which is soft enough to elastically yield to pressure, but which at the same time is hard enough to resist wear to a marked degree.

What is claimed is:—

35 1. A belt cleaner comprising a body or

Washington, D. C."

backing member with a laterally extended seat therein, and a laterally extended block of rubber mounted in the seat and projecting beyond the backing and there provided with a laterally and longitudinally extended 40 working face.

2. A belt cleaner comprising an elongated backing or body member having extended opposite ends formed into handholds, and an intermediate cavity or seat extending 45 both laterally and longitudinally between the handholds, and a block of rubber secured in the seat and projecting beyond the corresponding face of the body member, said block of rubber being provided with a laterally and longitudinally extended working face spaced from the backing member. 50

3. A belt cleaner comprising an elongated substantially rectangular and approximately flat body member with opposite terminal extensions constituting handholds and between said handholds having a cavity or seat formed in one face, and a substantially rectangular block of rubber secured in the seat and projecting therefrom, and having its 55 outer face substantially flat and laterally and longitudinally extended.

In testimony, that I claim the foregoing as my own, I have hereto affixed my signature in the presence of two witnesses.

RUSSELL S. GIBSON.
